TELEPHONE SET

Lyndall C. Pocock and Harold J. Turton, Aldwych, London, England, assignors to Western Electric Company, Incorporated, New York, N. Y., a corporation of New York

Application December 19, 1933, Serial No. 703,051
In Great Britain January 18, 1933

8 Claims. (Cl. 179—156)

This invention relates to microtelephonic headsets, for operators, for instance.

Normally an operator is provided with a single receiver mounted on a headband, and a transmitter with a horn-like mouthpiece which is carried on the chest by means of a harness.

This arrangement has a number of disadvantages, one of which is that the harness has a tiring effect on the neck muscles, and another of 10 which is that when the operator moves her head, the efficiency of the transmitter varies greatly.

The object of the present invention is to provide an operator's or like telephone set which is more simple in construction, lighter in weight, 15 which obviates the fatigue attendant on the use of the present type of operator's telephone set and in which the position of the transmitter relative to the mouth is not varied by movements of the head.

20 It has previously been proposed to mount the operator's transmitter assembly on the headband carrying the receiver or receivers, thus forming a microtelephonic headset, but the constructions proposed have been cumbersome, and so far as 25 we are aware have never been used in practice.

According to one feature of the invention an unenclosed microphone capsule is mounted on 30 an arm supported by a receiver headband. By "microphone capsule" is meant the microphone 35 unit which is usually enclosed in for instance the transmitter casing of a handset and access to which for the sound waves is usually given via a transmitter mouthpiece.

According to another feature of the invention a 35 transmitter is mounted on an arm carrying a clip 40 adapted to embrace the receiver casing so that the transmitter assembly can be fitted to existing headsets.

According to a further feature of the invention, 45 a microtelephone headset comprises a single receiver and a transmitter carrying arm which is so shaped and so jointed to the transmitter and to the headset that the transmitter can be arranged in the correct position for speech when the receiver is worn on either ear.

According to yet another feature of the invention a microtelephonic headset, including transmitter, supporting arm, receiver, headband and leads, is so constructed and arranged that 50 every portion of its surface which is liable to be touched during use is electrically dead.

The invention will be more clearly understood from the following description of one embodiment of the invention shown in the accompanying drawings in which:—

Fig. 1 shows a general view of an operator's microtelephonic headset.

Fig. 2 shows in cross-section the microphone capsule and the joint connecting the capsule to the supporting arm, 5

Fig. 3 shows in front and side elevation the clip by which the transmitter-carrying arm is mounted on the receiver casing and the joint connecting the clip to the transmitter-carrying arm.

The headband 1 carries an ear or head contact- 10 pad 2 and a receiver casing 3. On the receiver casing is mounted a clip 7 which is connected to a tubular arm 4 by a ball-joint 8. A microphone capsule 5 is rotatably connected to the arm 4. The receiver leads of the four-conductor cord 9 15 are connected direct to the receiver terminals which are enclosed in known manner, but the transmitter leads are connected to a terminal plate carried by the clip 7. Leads from the terminal plate pass through the ball of the ball-joint 20 8 and the arm 4 to the microphone.

Referring to Fig. 2, the capsule is of the type described in British Patent No. 348,716, complete accepted May 21, 1931, comprising a back electrode 15 fixed to the capsule casing, a silk granule 25

chamber 16 fixed to diaphragm 18 which is apertured to receive the front electrode 17. The capsule is mounted on a cup-shaped insulating block 30 13 by rivets 23. The diaphragm 18 is mounted between clamping rings which are insulated from the casing by a cellulose acetate or silk disc and a paper cup 19. A contact ring 20 is positioned between the paper cup 19 and one of the clamping rings and an extension 24 thereof rests on an insulating block and bush 25 and is connected to a 35 terminal 21 by one of the rivets 23 which is insulated from the capsule casing by the bush 25. The block 13 is peripherally grooved to receive a metal cylinder 11 enclosing the terminal 21 electrically 40 connected to the diaphragm and the terminal 14 electrically connected to the back electrode by a bolt passing through the block 13 and through an oversize hole in the capsule casing. Punched-out 45 positioning lugs 26 on the capsule casing engage recesses in an insulating spacing block 27 surrounding the bolt. The back of the cylinder 11 is closed and the cylinder held in position by an insulating disc 12 screwed to the block 13. A tubular member 6 has splayed ends partially embracing the cylinder 11 and riveted thereto. The 50 member 6 receives one end of the arm 4 and a rivet 10 passes through the member 6 and slots in the arm 4 of such a length as to allow 50 degree rotation of the arm in the member 6.

Referring to Fig. 3, the ends of the clip 7 are 55

turned in to form a seating for a terminal plate 37 and have parallel extensions 38. A square plate 34 is riveted to each extension 38 with its side diagonal to the axis of the extension. Apertures 35 are formed in each extension 38 and each plate 34, and other apertures are formed in each plate and extension when the members are riveted together. The terminal plate 37 is screwed at each end to the seating on the clip, the screws also carrying terminals to which are connected the transmitter leads of the cord, and which are protected from contact with the wearer by the clip. A ball and sleeve 39, 31 is mounted on the end of the arm 4 and is riveted thereto. A projection 32 is formed on the sleeve 31 to cooperate with the shaped extensions 33 of the clip to restrict rotation to 180°. The restriction of rotation is to prevent injury to the leads. The ball 39 is positioned between the plates 34 engaging them in the apertures 35 and the plates are drawn together by bolts 36 sufficiently to hold the ball joint in adjusted position. Leads 38 connected to the terminals on plate 37 pass through the tubular arm 4 and are connected to the terminals 14, 21, Fig. 2. It will be observed that every portion of the surface of the headset is electrically dead.

The arm, joints, and transmitter capsule casing are made of aluminium or aluminium alloy. The transmitter attachment is thereby made very light in weight, the additional load carried by the head being very small. It will be seen that by swivelling the arm 4 about the universal joint and rotating the capsule 5 on the arm, it can be positioned in front of the arm when the receiver is on the right ear and when the receiver is on the left ear.

What is claimed is:

1. In combination, a microphone capsule, a rod-like member, a receiver clip, a terminal block of insulating material supported by said clip, said rod-like member being hollow for the passage of conductors between the capsule and the terminal block, and a swivel connection, said capsule being adjustably secured to one end of said member, and said receiver clip being secured to the other end of said member through said swivel connection.

2. In combination, a microphone capsule, a rod-like member, a receiver clip for engagement with a receiver to be held against either ear of a user, said clip having a pair of depending spaced portions, and a swivel connection between said spaced portions and having a projection for engagement with the spaced portions to limit the degree of rotation of the swivel connection, said capsule being adjustably secured to one end of said member, and said receiver clip being secured to the other end of said member through said swivel connection.

3. In combination, a microphone capsule, a rod-like supporting member, a receiver clip, a terminal block supported on said receiver clip, and a hollow ball joint connection, said capsule being adjustably secured to one end of said member, and said clip being coupled to the other end

of said member through said connection, said member being hollow for the passage of conductors therethrough and through the hollow ball joint connection to said terminal block from said capsule. 5

4. In combination, a microphone capsule, a hollow, rod-like supporting member, a receiver clip comprising arcuate portions for engagement with a receiver to be held against a user's ear and planar portions defining a shelf portion below such a receiver, and a swivel connection, said capsule being adjustably secured to one end of said member, and said clip being coupled to the other end of said member through said connection. 10 15

5. In combination, a microphone capsule, a rod-like member, and a band member to be clamped around a receiver to be held against the user's ear, such capsule being secured to one end and said band member to the other end of said 20 rod-like member, and said band member having a shelf portion and a terminal block of insulating material supported on said shelf portion, said rod-like member being hollow for the passage of conductors between the capsule and the terminal 25 block.

6. In combination, a microphone capsule, a receiver clip comprising arcuate portions for engagement with a receiver to be held against a user's ear, planar horizontal portions defining a 30 shelf portion beneath such a receiver, and planar vertical portions immediately below said shelf portion, swivel means supported on said planar, vertical portions, and a one-piece, rod-like member connected with said swivel means at one end, 35 and supporting said capsule at its other end.

7. In combination, a microphone capsule, a receiver clip comprising arcuate portions for engagement with a receiver to be held against a user's ear, planar horizontal portions defining a 40 shelf portion beneath such a receiver, and planar vertical portions depending from said shelf portion, swivel means supported on said planar vertical portions, a rod-like member connected with said swivel means at one end and supporting 45 said capsule at its other end, and a projection on said swivel means for engagement with said planar vertical portions of the clip to limit the swivel to a range of 180 degrees.

8. In combination, a microphone capsule, a 50 receiver clip comprising arcuate portions for engagement with a receiver to be held against a user's ear, planar horizontal portions defining a shelf portion beneath such a receiver, and planar vertical portions depending from said shelf portion, swivel means supported on said planar vertical portions, a rod-like member connected with said swivel means at one end and supporting said capsule at its other end, said capsule being adjustable through an angle of 50 degrees, and a 55 projection on said swivel means for engagement with said planar vertical portions of the clip to limit the swivel to a range of 180 degrees. 60
